ATION OF CONNECTICUT

ANTIRATTLE DOVETAIL FOR DOORS

Application filed July 30, 1930. Serial No. 471,696.

The present invention relates to improvements in self-adjusting anti-rattle dovetails, particularly for automobile doors, an object being to provide a device of this character comprising cooperating socket and wedge elements, and in which the socket element forms a structural composite part of the metal post of the door frame, as distinguished from the usual type of dovetail in which the 10 socket member is provided as an attachment to the door frame. The present arrangement greatly simplifies assembly and provides a permanent, reliable and accurately positioned socket. It is proposed in the present embodiment to provide a dovetail in which the socket member is provided with laterally adjustable resiliently supported dovetail members adapted to have a wedge member engaged between them, the respective 15 dovetail members being supported against vertical movement, and which are adapted to retain the door against vertical vibration, and compensate for wear, lateral movement, and variations in the vertical and lateral alignment 20 of the door.

A still further object is to provide a device in which the dovetail members will be protected from excessive wear and breakage, and may be made of a self-lubricating substance, such as fibre, bakelite or the like, to the end 25 that the device will have a long life, and the necessity for lubricating the same will be eliminated.

With the above and other objects in view an embodiment of the invention is shown in the accompanying drawing, and this embodiment will be hereinafter more fully described with reference thereto, and the invention will 35 be pointed out in the claims.

In the drawing:—

Fig. 1 is a perspective view of a portion of the outer side of the metal door frame post with the dovetail socket, according to the 40 present embodiment of the invention.

Fig. 2 is a perspective view of the end of the door showing the wedge member mounted thereon, the door being shown in dotted lines, while the wedge member is shown in 45 full lines.

Fig. 3 is a front elevation of the wedge member.

Fig. 4 is an edge view thereof.

Fig. 5 is a front elevation of the inner casing part of the socket element before attach- 55 ment to the post.

Fig. 6 is a front elevation of the socket assembled to the post.

Fig. 7 is an end view thereof.

Fig. 8 is a rear elevation of the same.

Fig. 9 is a sectional view taken along the line 9—9 of Fig. 6.

Fig. 10 is a view similar to Fig. 6 and showing the wedge member in cross-section en- 65 gaged in the socket.

Fig. 11 is a perspective view of one of the block members employed.

Fig. 12 is a front elevation of a modified form of inner casing before attachment to the post.

Fig. 13 is an end view thereof.

Similar reference characters indicate corresponding parts throughout the several figures of the drawing.

Referring to the drawing, the device, according to the present embodiment of the invention, comprises a socket element incorporated as a structural part of the metal post of the door frame 10, and a wedge element adapted to be secured to the edge of the door 11 in relation to enter the socket upon closing of the door.

The metal post 10 of the door frame is bent along a vertical line to form a right angular corner, against which the door closes. A 85 rearwardly converging opening 12 is cut in the corner of the post, the forward portion of which has its upper and lower edges disposed in parallel relation and its end edge vertically disposed.

The inner or box part of the socket is formed from sheet metal and as shown in Fig. 5 comprises a rectangular portion 13 having wall flanges 14, bent from its upper and lower and rear edges, and outwardly extending base flanges 15 bent from the upper and lower wall flanges. A pair of inwardly bent lugs 16 are struck from the rear wall flange for supporting the ends of the springs, present- 95 ly to be more fully referred to.

The box thus provided is somewhat wider than the opening 12 and upon its forward edge there is provided a projecting lip 17 of such dimensions as to enter the opening 12 to seat upon its vertical edge, and to project slightly beyond it, the projecting portion being bent at a slight angle. When so engaged the base flanges 15 lie flat upon the inner surface of the post, their forward edges abutting the inner surface of the flange of the post, and in this relation the box is secured by spot-welding the base flanges to the post at suitable points, as indicated at 18, Fig. 8.

It will be seen that the lip, with its angularly bent edge accurately positions the box upon the post so that it may be secured in its proper relation with the greatest facility, and in the assembled relation prevents distortion of the box through strains imposed upon it. The lip has the further advantage of forming a guide surface for the wedge element as it enters the socket.

A pair of opposed block members 19 of generally rectangular shape are disposed within the casing, these blocks having flat parallel surfaces 20 adjacent the inner ends in sliding engagement with each other, and cooperating with the upper and lower parallel walls of the casing to prevent vertical displacement of the blocks. Inclined slightly arcuate faces 21 extend from the flat faces 20 to the forward ends of the blocks in diverging relation to each other. Pockets 22 are provided in the rear walls of the blocks within which are engaged coil springs 23 positioned upon the lugs 16 of the casing, and which press the blocks forwardly against the flange of the post, as shown in Fig. 6, while permitting the blocks to be forced laterally inwardly as shown in Fig. 10. In both positions the inclined faces 21 are projected into the opening 12.

The blocks may be assembled within the casing through the opening 12, this being done conveniently by first inserting one of the blocks and its spring, and then inserting the other block and its spring, pressing the first block inwardly while the second block is being inserted. The blocks may be of any suitable material, and because of the protection against breakage afforded by the casing, may be of fibre, bakelite, or other suitable squeak preventing, self-lubricating material.

The wedge member comprised an attaching base 24 having screw holes 25, and a rigid projecting wedge-shaped projection 26, having flat inclined sides 27, substantially corresponding to the inclination of the dovetail blocks.

The slightly arcuate shape of the inclined surfaces of the blocks permits firm engagement of the wedge member irrespective of slight variations in the vertical alignment of the door. Obviously this arrangement may be reversed, if desired, and the inclined sur-

faces of the wedge member made slightly arcuate, the inclined surfaces of the blocks being flat.

In Figs. 12 and 13 we have shown a modification in which the block members 19 are adapted to be assembled and held in the box casing before the latter is attached to the post. For this purpose lugs 28 are formed upon the forward edges of the upper and lower wall flanges 14, being bent inwardly so that their forward surfaces are flush with said forward edges of the wall. In the forward ends of the block members there are provided pockets 29, of corresponding depth to the metal thickness of the lugs, and within which the latter engage with the forward end surfaces of the blocks in flush relation to the forward edges of the box, so that the same may be assembled against the flange of the post in exactly the same manner as the box illustrated in Fig. 5. The engagement of the lugs 28 in the pockets 29 not only retains the blocks against the outward pressure of the springs, but so interlock with the pockets as to prevent displacement through the open side of the box, thus permitting the box with the assembled blocks to be handled and shipped in quantities without danger of the blocks becoming displaced.

The operation is as follows:—

When the door is in open position the blocks are projected forwardly against the flange of the post as indicated in Figs. 1 and 6. As the door is closed the wedge member 25 engages between the blocks, contacting therewith before the door is completely closed, the complete closure of the door causing the blocks to be moved laterally against the pressure of the springs which hold the blocks snugly against the wedge member, while the inclination of the engaging surfaces is such that vertical pressure will not displace the blocks and cause vibration.

The door is provided with the usual latch not shown, which engages behind a striker on the door frame, and the present device is such that it permits the door to close sufficiently to allow the latch to operate, and thereupon exerts an outward pressure on the door to force the latch bolt tightly against the striker. Upon release of the latch the device exerts an opening pressure on the door.

Should the wedge member be out of alignment with the socket, due to sagging of the door or inaccurate mounting of the wedge member, the independent movement of the respective blocks will permit them to adjust themselves to the wedge surfaces and perform their cooperative retaining function.

We have illustrated and described a preferred and satisfactory embodiment of the invention, but it will be obvious that changes may be made therein, within the spirit and

scope thereof, as defined in the appended claims.

Having thus described our invention what we claim and desire to secure by Letters Patent is:—

- 5 1. In an anti-rattle device for doors, the combination with a door frame metal post forming an angular corner and having a wedge receiving opening, of a casing adapted to be engaged at the inner side of said post and having a projecting lip portion adapted to engage in said opening to accurately position said casing with respect thereto, wedge engaging means disposed in said casing, and
- 10 15 a wedge member adapted to be engaged therewith through said opening and to be guided by said projecting lip.
- 20 2. In an anti-rattle device for doors, an outer casing portion having a wedge receiving opening, and an inner casing portion adapted to be assembled with said outer casing portion and having an open side adapted in assembled relation to be engaged by said outer casing portion, resiliently mounted
- 25 block members mounted in said inner casing portion, and lugs bent from said inner casing portion for retaining said blocks therein in compressed relation independently of said outer casing portion.
- 30 3. In an anti-rattle device for doors, the combination with a door frame metal post forming an angular corner and having a wedge receiving opening, of a casing adapted to be engaged at the inner side of said post and having a projecting lip portion adapted to engage in said opening to accurately position said casing with respect thereto and having an angularly bent extension projecting beyond said opening, wedge engaging
- 35 40 means disposed in said casing, and a wedge member adapted to be engaged therewith through said opening and to be guided by said projecting lip.

Signed at Bridgeport, county of Fairfield,
45 and State of Connecticut, this 11th day of July, 1930.

RAYMOND G. MOORE.
ARTHUR CLAUD-MANTLE.
